COMBINED DISPLAY AND DISPENSING STAND

George P. Stropkay, 100 W. Hickory,
Bloomfield Hills, Mich.

Filed Aug. 3, 1964, Ser. No. 81,131

Term of patent 14 years

(Cl. D80—9)

FIG. 3

I claim:

The ornamental design for a combined display and dispensing stand, substantially as shown and described.
